UNITED STATES PATENT OFFICE.

FRANK E. PHINNEY, OF RIVERSIDE, CALIFORNIA.

DESIGN FOR A PATRIOTIC BADGE.

51,046.

Specification for Design. Patented July 17, 1917.

Application filed May 28, 1917. Serial No. 171,586. Term of patent 3½ years.

To all whom it may concern:

Be it known that I, FRANK E. PHINNEY, a citizen of the United States, residing at Riverside, in the county of Riverside and State of California, have invented a new, original, and ornamental Design for Patriotic Badges, of which the following is a specification, reference being had to the accompanying drawing, forming part thereof.

The figure is a front view of a patriotic badge, showing my new design.

I claim:

The ornamental design for a patriotic badge, as shown.

FRANK E. PHINNEY.
